UNITED STATES PATENT OFFICE.

WILLIAM R. HARTIGAN, OF BURLINGTON, CONNECTICUT.

BOTTLE.

SPECIFICATION forming part of Letters Patent No. 568,613, dated September 29, 1896.

Application filed June 27, 1894. Serial No. 515,870. (No model.)

To all whom it may concern:

Be it known that I, WILLIAM R. HARTIGAN, a citizen of the United States of America, residing at Burlington, in the county of Hartford and State of Connecticut, have invented 5 a certain new and useful Improvement in Bottles and the Like, of which the following is a description, reference being had to the accompanying drawing, wherein the figure 10 is a view in central vertical section of a bottle embodying said improvement.

The object and purpose of the improvement is the production of a bottle or like vessel which cannot be refilled after the original 15 charge of liquid has been poured out.

The letter *a* denotes the body of the vessel or bottle proper, and *b* denotes the neck thereof, in the mouth of which a cork or other stopper may be fixed.

20 The letter *c* denotes a valve-cage containing the ball-valve *d* and its seat below it. Above the valve the cage is formed into a dome obstructing the bottle-neck against the escape of the valve and preventing improper 25 access thereto, but permitting the outward flow of liquid through perforations *c'*.

The original charge of liquid is placed in the bottle before the valve-cage is set to place.

A mode of securing the valve-cage in place 30 is to provide an annular groove in the periphery of the valve-cage, a corresponding annular groove in the inner face of the bottle-neck, and a ring *e* of rubber or other elastic material fitting these two grooves. By the 35 use of this arrangement the valve-cage can

be pressed downward into place where it will be held by the rubber ring. The dome of the valve-cage is so thin that if it be attempted to pull the valve-cage from its seat the dome will break and thus destroy the integrity of 40 the seal.

The word "bottle," as used herein, means any vessel to which this improvement is applicable, and the word "rubber" means any material which will serve the purpose of the 45 rubber.

I claim as my improvement—

The bottle *a* formed with a neck having an interior annular groove therein and an interior annular shoulder located below the annular 50 groove, a valve-case formed with an exterior annular groove located and arranged to aline with the annular groove in the neck of the bottle the said valve-case being constructed to accurately fit the neck of the bottle and to be 55 seated and sustained on the interior annular shoulder thereof, whereby a liquid-tight joint is formed to protect a packing in the said groove, the said valve-case being also formed with an integral fragile dome rising from the 60 base of the valve-case and having apertures therein, a ball-valve in the valve-case, and an elastic ring to engage in the alined grooves of the valve-case and the neck of the bottle, all combined, constructed and arranged as 65 and for the purpose specified.

WILLIAM R. HARTIGAN.
